United States Patent Office

Des. 220,745
Patented May 18, 1971

220,745

GLASS CUTTING TOOL

Stephen J. Kovacik, Rossford, Ohio, assignor to Libbey-Owens-Ford Company, Toledo, Ohio

Filed Apr. 20, 1970, Ser. No. 22,514

Term of patent 14 years

Int. Cl. D8—02

U.S. Cl. D8—51

Fig. 1.

Fig. 2.

Fig. 3.

Fig. 4.

Fig. 5.

FIG. 1 is a perspective view of a glass cutting tool, showing a new design;

FIG. 2 is a perspective view of the tool as viewed in the opposite direction;

FIG. 3 is a view of the underneath side of the tool;

FIG. 4 is an elevational view of one side of the tool, and

FIG. 5 is an elevational view of the opposite side thereof.

I claim:

The ornamental design for a glass cutting tool, substantially as shown and described.
